RIFLE TARGET

Filed Jan. 31, 1928

INVENTOR.

Marwood D. Van Auken

UNITED STATES PATENT OFFICE.

MARWOOD D. VAN AUKEN, OF NEW YORK, N. Y.

RIFLE TARGET.

Application filed January 31, 1928. Serial No. 250,896.

This invention relates to rifle targets, and particularly to that class in which the target proper is provided with an automatically operative magazine for frangible and successively fed target centers and with unobtrusive seats for holding such centers individually in concentric position relative to the target.

The main object of my invention is to provide a target of the character with an automatically replaced center, commonly called "bull's eye," which will be readily shot to pieces by even a good buck shot in such manner that the resulting fragments of the fractured center will immediately be shed by the target and permit a whole and new center to fall into position.

Another object is to provide a target of this nature with a vertically arranged magazine or chute for the successive centers, and to further introduce a resiliently held hammer in the center of the target to receive the impact of the shot and then strike a bell or produce a signal indicating a perfect shot.

Other objects and the novel advantages accruing from the combination of novel and useful features comprising my invention will appear hereinafter as this specification proceeds.

In the accompanying drawing forming part hereof,—

Fig. 1 is a front view of a target made according to my invention and embodying the same.

Fig. 2 is a fragmentary view of the same, in which a shot is included with a fractured target center at the moment of impact of the bullet.

Fig. 3 is a vertical section in part of the device of Fig. 1, the upper part being a simple side view of the same.

Fig. 4 is a group of target centers in several positions.

Throughout the views, the same reference numerals indicate the same or duplicate parts.

In rifle practise, it is almost universally the custom to use a target of some nature for improving marksmanship, but, as a rule, there is no interesting incentive, aside from the actual shooting which will urge prospective marksmen to continue in their practice until great proficiency is attained. In order to provide additional interest and more obvi-

ous competition between members of such a group of marksmen, and a distinct novelty, as well, it is herewith proposed to have a target plate 1 provided with a frangible center or bull's eye 2 which is normally supported in position by a pair of pins 4, 4. On the target is secured a chute or magazine consisting of the front wall 5, rear wall 6 and side walls 15 and 16, the lower end of the front wall terminating in a lip 5' which assists in retaining the center disk 2 in position.

The disks are made of very frangible material such as dry baked clay, plaster of Paris or other readily fractured compositions, even glass. The center disks are fed in at the top 18 of the magazine, the lowest disk being drawn down by gravity to rest on the pins 4, 4 already mentioned, when the same disk is in position for a shot. When a bullet strikes as at 13 in Fig. 2, it will instantly shatter the disk into a number of fragments as at 14, 14, while the impact of the bullet will be received by a plunger or hammer 7 located immediately behind the disk. This hammer is resiliently supported by a spring 8 which is fast to the target. Then, again, a bell 10 is secured upon a rear bracket 9 in such a position as to be directly struck by the hammer 7 when a bullet impinges on the hammer, whereby an audible signal will be had.

On the other hand, the disks may be composed of such a mixture as to produce light when shattered, steel filings and sand with a small amount of gunpowder or other explosives may be incorporated with the plaster or clay, the purpose being to create an interesting novel effect when making a good shot.

The target as a whole may be stood on a lower bracket 17, or it may be hung up by the aperture 12 in an upper bracket 11.

It is manifest that when a disk has been smashed by the impact of a bullet the series of disks above in the magazine will drop with the next disk which will immediately fall into position on the target pins. And among the disks may be fed in at intervals variously colored disks, the preferred color of the regular disks being white for visibility at great distances.

Modifications of my invention may, of course be made, such as disposing the disk magazine horizontally or even inverting the same and then forcing the disks into position by means of a spring instead of gravity, or a

switch may be substituted for the rear bell so that an accurate shot may close the circuit of a signal light or similar indicator.

Having now fully described my invention,
5 I claim:—

1. A target including a target-plate having a frangible centre supported in such manner as to be shed over the face of the target when fractured by the impact of a bullet, a magazine of duplicate frangible centres automatically feeding a new centre to the position of support on the face of the target, and covering on the entire face of the magazine to protect the frangible centres against impact of a bullet.
- 10 2. A target including a target plate having a magazine for successively fed target centers, means on the plate to individually support one disk on the front of the target plate in central position until shattered and the fragments freely shed across the face of the target by the impact of a bullet and protective means on the face of the magazine to prevent impingement of a bullet with any of the target centres except the single disc that has reached the position of support in the centre of the target.
- 15 3. A target including a target plate having means thereon to support a replaceable target center on the front or face of the target, a frangible target center for said target plate registering with said supporting means when whole in a manner whereby when shattered the fragments are free to fly radially across the front of the target plate, a magazine to feed the frangible target centre from a point remote from the target-plate and protective means for the front of the magazine whereby impingement of the bullet is presented to assure non-shattering of the frangible centre throughout its feed until reaching its position of support in the centre of the target.
- 20 4. An automatically-fed breakable-bull's-eye target having means to automatically replace each broken bull's-eye on the front of the target, supporting means for each unbroken bull's-eye permitting radial flight or

shedding upon fragmentation across the front of the target and means to protect the breakable bull's-eye targets throughout the course 50 of their automatic feed.

5. A target means to feed automatically fragile discs to the centre of the target front or face, a plurality of fragile discs, means for supporting each disc before shattering in 55 a manner whereby a bullet impact will splash the fragments across the face of the target and means to protect the fragile disc throughout the automatic feeding of the discs.

6. A magazine bull's-eye target having an 60 automatic feed for breakable bull's-eye discs, a series of different colored discs adapted to be fed to the centre of the target, means for support of each disc as centered whereby upon shattering by bullet impact the fragments are 65 free to splash across the face of the target, and a different colored disc thereupon automatically fed to the front of the target centre.

7. A target for small arms use, comprising 70 a target face, means to support successive discs to represent the bull's-eye of the target, a plurality of discs adapted to rest in said supporting means and each containing in said disc a light producing material when the disc is shattered, said supporting means permitting 75 the shattering of the disc over the face of the target.

8. A practice target for small arms, comprising a frangible disc containing a mixture explosive upon impact of a bullet, means to support said disc before impact centrally on the face of a target and permit its shattering visible from the front of the target.

9. A practice target for small arms, comprising a frangible disc permitting light and smoke upon impact of a bullet, means to support said disc before impact centrally on the face of a target and permit its shattering visible from the front of the target.

In testimony whereof, I, MARWOOD D. VAN 90 AUKEN, have signed my name to this specification.

MARWOOD D. VAN AUKEN.
